CLAIM

We claim the ornamental design for a television camera, as shown and described.

DESCRIPTION

FIG. 1 is a front perspective view of a television camera according to the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view thereof taken along line 9-9 of FIG. 3;

FIG. 10 is a cross-sectional view thereof taken along line 10-10 of FIG. 3;

FIG. 11 is a cross-sectional view thereof taken along line 11-11 of FIG. 3;

FIG. 12 is a cross-sectional view thereof taken along line 12-12 of FIG. 3; and,

FIG. 13 is a cross-sectional view thereof taken along line 13-13 of FIG. 3.

The broken lines in the drawings form no part of the claimed design. Broken lines formed by equal length dashes show unclaimed subject matter.

1 Claim, 13 Drawing Sheets
